UNITED STATES PATENT OFFICE.

GEORGE W. FISHER, OF ST. LOUIS, MISSOURI, ASSIGNOR OF ONE-HALF TO
THE FULTON IRON WORKS, OF SAME PLACE.

BAGASSE-BURNER.

SPECIFICATION forming part of Letters Patent No. 340,302, dated April 20, 1886.

Application filed December 15, 1885. Serial No. 185,748. (No model.)

To all whom it may concern:

Be it known that I, GEORGE W. FISHER, of St. Louis, in the county of St. Louis and State of Missouri, have invented certain useful Improvements in Bagasse Burners or Apparatus, of which the following is a specification, reference being had to the accompanying drawings, in which—

Figure 1 is a plan view of my improved apparatus. Fig. 2 is a section of the same on the line 2 2 of Fig. 3. Fig. 3 is a longitudinal vertical section of the same; and Fig. 4 is a section on the line 4 4 of Fig. 3.

Heretofore bagasse-burners have been imperfect in construction and wasteful in their operation.

My object is to produce a rapid rate of combustion by means of a burner supplied with a forced draft, to perfect the combustion by reverberation, and to utilize the products of combustion to the best advantage and with the least waste of heat.

In some bagasse-burners openings have been made in the top, both for supplying the bagasse and for the escape of the products of combustion. In these burners combustion is slow and imperfect, and the heat is not utilized. In other bagasse-burners an opening has been provided in the top for receiving the bagasse and another opening below for permitting the products of combustion to pass out and underneath boilers and thence out through a high chimney. In some of these latter furnaces, I believe, blowers have been used to improve the draft. This is an improvement upon those first described, but is still far from satisfactory.

In connection with my burner I provide a small opening at the top through which, by means of feed-rollers receiving the bagasse from an endless belt or carrier directly from a cane-mill, it is delivered into the burner. This burner is provided with a furnace at its bottom, a fire-bridge at one side of the furnace, and a reverberatory arch on the same side, making an opening low down in the burner through which the products of combustion pass, and thence impinge against the lower surfaces of a nest of low-down boilers, and finally pass out through the boiler-flues into a chimney. I also provide a series of tuyeres and a blower to force a draft and stim-

ulate combustion. The result is I get rapid initial combustion of the bagasse in the burner, then reverberatory action upon the hot gases, causing their combustion, and finally the utilization to the best advantage of the high degree of heat produced for raising steam.

Referring, now, to the drawings for a description in detail of my improved apparatus, A indicates the bagasse burner or chamber; B, the furnace below it; C, the reverberatory-furnace, and D the low-down nest of boilers.

To go more into detail, E indicates an endless belt or carrier, which may be assumed to be for the purpose of delivering the bagasse as it comes from an adjacent cane-mill, where the juice is pressed from the cane and the residuum or bagasse-fiber is delivered onto the endless belt, thence down a chute, or it may be into a hopper, F, to feed-rolls G, which pass it into the interior of the burner directly over the furnace. In this furnace H indicates the grates, I blow-pipes, which may be supposed to be connected with an ordinary blower that forces air through them, thence through the tuyeres K into the fire-box L. The products of combustion pass thence over the fire-bridge M into the reverberator, having its side walls and crown of fire-brick N supported by fire-brick piers O. The arch is depressed, as shown in the section Fig. 3, so that the products of combustion are driven more directly against it than they would otherwise be to secure better reverberatory action on the gases, as is well understood in the construction of reverberatory-furnaces. At the same time this arch is increased in width, as illustrated in Fig. 1, at the end where it enters under the boilers P. Thus combustion of the gases is promoted and intensified, and the heat is evenly distributed upon the exposed boiler-surfaces.

I prefer to use boilers of the type illustrated, in which inclined tubes Q, connecting with one end of the boiler and lower down with a mud-drum R at the other, are employed. This mud-drum is connected by vertical tubes or legs S with the opposite end of the boiler, which is provided with fire-flues (not shown) in its interior, and a chimney T, as is well understood. This form of boiler, which is well known, gives an excellent circulation of water and a thorough utilization of heat for

steam-generation. Another boiler, or series of boilers, U, at right angles with the lower nest may be employed, if desired.

The arrows in Fig. 3 indicate the direction of delivery of the bagasse into the burner, and also the direction taken by the products of combustion.

V indicates an opening provided with a tight-fitting door on one side of the burner for cleaning it out.

Having thus described an apparatus containing my improvements, what I claim as new, and desire to secure by Letters Patent of the United States, is—

15 1. The combination of the bagasse-chamber A, the furnace B, below the floor or hearth of the chamber A, a side opening, V, for cleaning out the bagasse-chamber, a receiving opening at the top of the bagasse chamber provided with feed-rollers, and a reverberatory arch at one side, substantially as described.

20 2. The combination, with a bagasse-burner having a feed-opening at its top and a furnace at its bottom, of blow-pipes and tuyeres

below the bottom of the burner and a reverberatory arch at one side, substantially as set forth.

3. The combination, substantially as set forth, of the bagasse-chamber having a feed-opening in its top, a furnace located directly under said opening and below the floor of the chamber, a discharge-opening at one side of the chamber, and the reverberatory arch over said discharge-opening, substantially as described.

4. The combination of the burner A, having a feed-opening at its top and a furnace below its floor, of the fire-bridge and the reverberatory arch depressed and widened as it extends away from the opening into it from the burner, substantially as described.

In testimony whereof I have hereunto subscribed my name.

GEORGE W. FISHER.
